Specification for Design.

Patented May 27, 1913.

Application filed January 17, 1913. Serial No. 742,731. Term of patent 7 years.

To all whom it may concern:

Be it known that I, CHARLES NELSON, a citizen of the United States, and a resident of the borough of Brooklyn, county of Kings, city and State of New York, have invented a new, original, and ornamental Design for Vapor-Lamps, of which the following is a specification, reference being had to the accompanying drawing, forming a part hereof, in which—

Figure 1 is a side view, and Fig. 2 is a plan view of the lamp.

The design comprises a font of circular plan, with sides which swell outwardly, then

inwardly upon curved lines, as shown. Near the top is a bead, as shown. The wick tube is circular in plan, and carries a priming pan, as shown, and a perforated burner, as shown. The burner merges into the tube by means of open work, formed of radiating arms, each with a series of holes therein.

I claim:

The ornamental design for vapor lamp, as shown and described.

CHARLES NELSON.
